UNITED STATES PATENT OFFICE.

ERNST WILHELM BRACKELSBERG, OF HAGEN, PRUSSIA, GERMANY.

TYPE-WRITING MACHINE.

SPECIFICATION forming part of Letters Patent No. 335,887, dated February 9, 1886.

Application filed October 19, 1885. Serial No. 180,327. (No model.) Patented in Germany December 16, 1884, No. 31,985; in Belgium February 20, 1885, No. 67,945; in France February 21, 1885, No. 167,205; in England February 27, 1885, No. 2,688, and in Austria-Hungary June 27, 1885, XXXV, 1,116, and XIX, 1,114.

To all whom it may concern:

Be it known that I, ERNST WILHELM BRACKELSBERG, a subject of the King of Prussia, and residing at Hagen, Westphalia, Kingdom of Prussia, German Empire, gentleman, have invented a new and useful Improved Type-Writer, also applicable for stamping matrices, (patented in Germany December 16, 1884, No. 31,985; Belgium, February 20, 1885, No. 67,945; France, February 21, 1885, No. 167,205; Great Britain, February 27, 1885, No. 2,688, and Austria-Hungary June 27, 1885, respectively Tom. XXXV, fol. 1,116, and Tom. XIX, fol. 1,114,) of which the following is a specification.

My invention relates to apparatuses known under the name of "type-writers;" and it consists in the means employed for printing or impressing letters or other characters in succession upon a sheet of paper or other material, for causing the spaces between the letters or characters composing a word to become uniform, and for regulating the width of these spaces, as hereinafter described and claimed.

The improved apparatus is represented on the annexed six sheets of drawings.

Figure 1 (divided into Figs. 1^a and 1^b) is a front view of the same; Fig. 2, (likewise divided into Figs. 2^a and 2^b,) a plan; Fig. 3, a transverse section on line z z. Fig. 1, looking from the left to the right. Fig. 4 is a front view of a portion of the apparatus, in which some parts have been omitted in order to show others more clearly. Fig. 5 is a bottom view corresponding to Fig. 4. Fig. 6 shows a section on line y y, Fig. 4. Fig. 7 is an enlarged portion of Fig. 5, serving to explain the operation of certain parts. Fig. 8 is a front view, and Fig. 9 a transverse section, of a modified part of the apparatus adapted to produce matrices for stereotyping. Fig. 10 shows a number of equivalents of certain parts.

The types are secured in a single row to the holder T, which is connected by the pieces a' to the stationary guide-bar a, so that it can slide thereon. If preferred, the holder and the types may, however, be made in one piece. The said type-holder is operated by the rod b, flexibly attached to an arm of the former by

means of a ball-and-socket joint, b', or other equivalent means, and carrying at its other end a handle, c, terminating in a beak, c². Close to the bar a there is a lever, e, having its fulcrum at e', and kept normally in a raised position by a spring, e², the said lever being movable in a plane parallel to the body of the types. To the lever e are attached ledges d, carrying a register of the characters of the types contained in the type-holder, and these characters are so arranged in respect to the types, and the length of the rod b is such that when the beak c² is placed upon one of the characters of the register the type corresponding thereto will be brought opposite to the end of the printing-bar D, serving to press the paper against the type.

For the purpose of guiding the operator in placing the beak c² on a character, so that the type may always be brought exactly into the required position, special means are provided. By preference these consist in plates d', having opposite to each character a triangular notch, d², the inclined faces d² whereof will conduct the beak c², provided with a knife-edge, to the proper point, if it should not have been placed thereon at once. The characters of the register are distributed upon two or more ledges d, in order to allow each notch to be made of such width as that the liability to commit errors while inserting the beak c² will be reduced as much as possible. The operation of bringing the beak c² to appropriate place is further facilitated by the fact that the ledges d, together with the notched plates d', are arranged at different elevations, or in lines which slant or incline upwardly as they depart from the pivot e', as seen in Fig. 1, each following one being placed higher than the preceding.

The form of the notches d² may be made different from the drawings, provided their sides d³ converge downward, so that the beak c² will not shift laterally after having been pressed down within the notch. (See Fig. 10, I.) Moreover, the notches may be replaced by conical holes in the plates d, Fig. 10, II, the beak c² being in this case made in form of a

round pin directed downward; also, a beak forming a triangular prism, or a cone may be used, respectively, with notches or holes having such form that the inclined sides d^3 of the said prism or cone will come in contact with the upper edges thereof only, Fig. 10, III and IV; or the arrangement is inverted by attaching projections, pins, prisms, or cones to the register, and forming the beak with a triangular notch or a hollow cone, or with a notch or a hole adapted to the said prisms or cones, Fig. 10, V to VIII, the object being in every case to conduct the beak c^2 , by the agency of two inclined surfaces, d^3 , into the desired position. These surfaces d^3 , I shall call "guides."

The printing-bar D, which is movable in a direction vertical to the face of the types, is connected to the lever e by means of the lever q and the rod h, so that when the lever e is depressed the printing-bar will be raised and press the paper W, Fig. 3, which is above it, against the type. The depression of the lever e is brought about by a pressure exercised on the same by means of the handle c and beak c^2 subsequent to the insertion of the latter into a notch. The handle c is provided with a plate, c', for laying on the forefinger while performing this operation. By these means a print of any single type may be obtained.

The sheet of paper W which is to be printed upon is held by a carriage, H, arranged to slide lengthwise upon the table f of the apparatus, and which, when this table is inclined, as shown in Fig. 3, may be guided with sufficient security by a single ledge in front of it; but other guiding means may be employed. The said carriage consists of a bottom plate, two standards at the ends thereof, and a bar, h, connecting the standards at the top and parallel to the bottom plate. In the said standards is mounted a roller, g, portions of which are faced with india-rubber, by means whereof the roller bears upon the sheet of paper slipped under the same. One of the pivots of the roller carries a ratchet-wheel, j, with which gears a pawl arranged to be operated by a handle, i, for the purpose of turning the roller, and thereby drawing the paper forward through the medium of the india-rubber facings when a new line is to be commenced.

The carriage H, with the paper upon it, is moved toward the left for every letter or character to be printed, or for every space required, by the following mechanism: To the aforesaid rod h is connected, by means of a link, l, one arm of an elbow-lever, l', having at the end of its other arm a pin, l², engaging in a slit, l³, at the end of a bar, m, which for the present may be supposed to be rigidly fixed to a bar, m'. This bar m' is connected by a curved link, m², to a rod, n', suspended with a slit, n⁴, on a pin, n, screwed into an upright arm, e³, of the lever e, the said rod n' being drawn downward and against the pin n by a spring, n⁵, fixed with one end to n, and with the other to a knob at the head of n'. Finally, a bar, G, is pivoted with one end on

the pin n², connecting the parts n' and m², while with its other end, which is bent obliquely to the bar h of the carriage H, and which has a suitable aperture, it embraces the said bar h in such a manner that when the pin n² is depressed the bar G will pinch the bar h, and thus become locked with the carriage, whereas so long as the pin n² is in its raised or normal position the bars G and h are independent of each other.

The operation of this mechanism is as follows: When the lever e is depressed, it draws, through its arm e³, the pin n, and the spring n⁵, upon the rod n', which, in acting on the bar G, causes the same to become locked with the carriage H. Meanwhile the pin l² of the elbow-lever l' slides in the slit l³ without acting; but when l² strikes against the left hand end surface of the slit l³ it pushes the united bars m and m' to the left, and this motion is transmitted, through the connecting-link m², to the bar G, which, being locked with the bar h, draws the carriage H with the sheet of paper to the left, so that a fresh portion of the latter will be presented to a type. The bar G thus acts as a silent feed-pawl. Thereafter the printing-bar D presses the paper W (on which a sheet of paper covered with printing-ink is placed, as usual) against the type above it. During the latter part of the downward motion of the lever e the spring n⁵ expands, under the strain brought to bear upon it after the pawl G has pinched the bar h, and thus allows the lever e, together with the pin n, (which then slides in the slit n⁴ of the rod n',) to be completely depressed, while the pressure on G remains nearly uniform.

I shall now proceed to show by what means the displacement of the paper-carriage is regulated and the blank spaces between all the letters in a word caused to become equal. For this purpose, in the first place, the types are arranged in the type-holder T, with spacing-pieces p, Figs. 4 and 5, between them, which are all of the same width, and on the front side of their lower end these pieces have an offset, whereby recesses p' are formed between the types; secondly, a lever, M, which I shall call the "gage-lever," is pivoted to a block, o, fixed to the bar m', the said gage-lever being pressed with its left-hand curved beak o² toward the types and the recesses p' by means of a spring, o', while on its right-hand end acts a curved finger, o³, Figs. 1, 4, 5, and 6, fixed to the lever e, so that when the lever e is in its raised position the finger o³ will keep the gage-lever M out of contact with the types, whereas when e is depressed the said finger allows the spring o' to press the gage-lever, with its beak o², against the type, or into the recess opposite to the said beak; thirdly, the bar m is connected to the bar m' by a pin, m³, screwed into bar m' through a slit, m⁶, in bar m, and by a spring, m⁵, attached with one end to a projection, m⁴, on bar m, and with its other end to the pin m³; this spring tending to draw the bar m, with the left-hand end of its slit m⁶,

against the pin m^3 ; fourthly, the notches d , or their equivalents, are so adjusted that when the beak c^2 is inserted into any one of them the corresponding type will be brought with 5 its right-hand edge into a certain definite position—say in a line with the right-hand surface of the printing-bar D, as shown by a dotted line in Fig. 7. Suppose this type to be the one for the letter “m” and the type following 10 to the left to have the letter “s” on its face. As has been stated, the bars m and m' begin to move to the left, under the pressure of the pin l^2 , after the carriage H and the pawl G have become locked together, and this condition is 15 not altered by the introduction of the spring m^5 , which is made strong enough to overcome the frictional resistances of the parts m' , m^2 , n' , G, and H. About at the same time that pin l^2 begins to act on m the finger o^3 has released 20 the gage-lever M, and the spring o has pressed it with the side of its beak o^2 against the type, being then in proper position for printing—i. e., in the present case against the type for “m.” The bars m and m' thereupon 25 moving forward, together with the gage-lever, cause the beak o^2 of the latter to slide across the type for “m” and into the recess between the same and the type for “s.” As soon as the beak o^2 strikes with its tip against this type, 30 the motion of the gage-lever, and consequently that of the parts m' , m^2 , and G, and of the paper-carriage, is stopped. The bar m may, however, continue to move forward, as its 35 elastic connection with the bar m' by means of the spring m^5 allows it to do so. This arrangement is required in order that the lever e may be completely depressed and the printing-bar brought to bear against the type after the bar m' and the paper-carriage have been 40 stopped.

The effect which the described operation of parts has on the spacing of the letters on the paper may best be explained by aid of Fig. 7, which shows to an enlarged scale, and from 45 below, a portion of the type-holder T with the beak o^2 of the gage-lever in two different positions. Supposing that while the beak o^2 is in its normal position (drawn in full lines) a point, w , be marked thereon opposite to the 50 right-hand edge of the type for “m,” and assuming, moreover, that u be the distance of the point w from the tip of the beak o^2 , x the width of the type opposite to the beak, and v the uniform width of the spacing-pieces p , (or 55 of the recesses p'), it will be apparent from the figure that the stroke of the beak is equal to $x+v-u$, or, expressed in words, that it is equal to the varying width of the types, plus the space v minus the length u ; therefore so long 60 as u remains unvaried the spaces between the letters printed on the paper will be uniform and equal to $v-u$.

When the lever e is released so that it will be raised by the spring e^2 , it first causes the 65 printing-bar D to be withdrawn from the type, and at the same time it allows the bar m , im-

pealed by the spring m^5 , to follow the pin l^2 as it recedes, and with which m is in contact by the left-hand end of slit l^3 . Simultaneously the pin n in rising allows the spring n^3 to contract, and thereupon raises the rod n' , whereby the feed-pawl G is first relieved of pressure and then positively raised with its outer end, so that the paper carriage becomes disengaged from G. Moreover, the finger o^3 , acting on lever M, withdraws the beak o^2 of the same from the types. When thereafter the left-hand end of slit m^6 has come into contact with pin m^3 , the bar m' , gage-lever M, link m^2 , and feed-pawl G move to the right, together with bar m , 70 until m strikes against a stop, t . The paper-carriage meanwhile remains at rest, as the pawl G is free to slide on h . During the final part 75 of the motion of e the pin l^2 moves along the slit l^3 to its right-hand end. The apparatus is 80 then ready for renewed action.

In the foregoing it was stated that the spaces between the letters printed on the paper will be uniform so long as the dimension u remains unvaried. The said dimension may, however, be varied, and the spaces between the letters thereby caused to become wider or narrower, as the case may be. This is attained by making the aforesaid stop t adjustable. In the drawings it is supposed to consist in an 90 eccentric segment pivoted to the frame of the apparatus and provided with a handle for turning it. In the measure as this stop is adjusted so as to allow the beak o^2 to recede more or less the aforesaid dimension u will be altered. Words to be rendered conspicuous 95 may thus be printed with wide spaces between the letters.

After a line has been finished the carriage H is moved back by hand up to an adjustable 105 stop, f' . Besides, the paper is shifted forward as much as is required for the height of a line by means of the handle i , operating the ratchet-wheel j .

In order to inform the operator when a line 110 is finished, there is fixed to the table f a bell, r , on which strikes a hammer, s , attached to one end of a lever, s' , bearing with its other end against the carriage H and arranged to be released at the proper moment.

The apparatus as described may be employed without alteration for producing matrices for stereotyping, it being only required for this purpose to replace the paper W by a sheet of soft pasteboard or other material 120 adapted to receive and retain sufficiently-deep impressions, and as is otherwise used for making matrices. I prefer, however, in this case to adopt the modified arrangement represented by Figs. 8 and 9, in which the types T are 125 mounted movably in the type-holder T, while the matrice-blank is supported by a stationary block, U. The types are pressed downward against the blank by an arm, D', attached to the lever e , and they are raised and 130 maintained in their normal position by means of springs, such as shown in the drawings.

For shifting the blank in the direction of the height of the lines, two rollers, g and g' , may be employed.

I claim as my invention—

5 1. The sliding type-carrier T , with types, the rod b , flexibly connected thereto and provided with beak c^2 , the lever e , carrying a register of the characters of the types, arranged to correspond with the types, as described, 10 guides d^3 , for guiding the beak c^2 in respect to the characters on lever e , and means, substantially as described, in connection with e , for producing contact between the type being in printing position and the material to be printed upon, all combined and co-operating substantially as specified.

2. The sliding type-carrier T , with types, the rod b , flexibly connected thereto and carrying beak c^2 , the lever e , guides d^3 , and the 20 printing-bar D , connected to lever e so as to be pressed against the type in printing position when e is depressed, all combined and co-operating substantially as hereinbefore set forth.

25 3. The combination, with the type-carrier T , rod b , beak c^2 , lever e , and guides d^3 , of the carriage H , connected to the lever e , substantially as specified, so that it shall be shifted forward when the said lever is depressed, substantially as and for the purpose described.

30 4. The combination, with the type-carrier T , rod b , beak c^2 , lever e , guides d^3 , carriage H , having the bar h , and feed-pawl G , acting on bar h , of the arm e^3 , with pin n , the spring n^3 , and rod

n' , having slit n^4 , the link m^2 , united bars m' and m , having the slit l^3 , elbow-lever l' , with pin l^2 , and link l , substantially as hereinbefore described, and for the purpose set forth.

5. The combination, with the type-carrier T , having recesses p' between the types, the rod b , beak c^2 , lever e , guides d^3 , carriage H , and a feed-pawl, arranged and operating substantially as described, to shift the carriage when e is depressed, of a gage-lever, M , and means, substantially as described, for pressing the lever M laterally against the types and into the recesses p' , for moving the same lengthwise, together with the feed-pawl, for allowing it to stop when it has traveled to the end of a recess, p' , and for limiting its retrograde motion, substantially as and for the purpose specified.

6. The combination, with the type-carrier T , having recesses p' , the rod b , beak c^2 , lever e , guides d^3 , carriage H , with bar h , pawl G , and means, substantially as described, in connection with e , for depressing and raising the outer end of G , of the gage-lever M , spring o' , curved finger o^2 , bar m' , with pin m^3 , spring m^5 , bar m , with slits m^6 and l^3 , elbow-lever l' , with pin l^2 , links l and m^2 , and stop t , substantially as and for the purpose set forth.

In testimony whereof I have signed my name to this specification in the presence of two subscribing witnesses.

ERNST WILHELM BRACKELSBERG.
